DEMOUNTABLE SCAFFOLD

Reginald D. Ryder, Bradner, Ohio, assignor to Sun Oil Company, Philadelphia, Pa., a corporation of New Jersey

Application February 26, 1954, Serial No. 412,970

4 Claims. (Cl. 304—2)

This invention relates to scaffolds and particularly to an improved scaffold of the portable type.

It is an object of the present invention to provide a scaffold consisting of a multiplicity of sections, the number of such sections being reduced to a minimum, each of simple design and easily handled.

A further object is to provide a demountable scaffold the sections of which are of reduced size and when separately handled can be passed through small openings for reassembly in limited space.

Still another object is to provide a scaffold which can be quickly erected and dismantled with minimum labor.

It is a further object of the invention to provide a scaffold of small sections capable of being erected in a limited space which because of the unique arrangement of the sections provides a strong, sturdy structure.

Yet another object is to provide a scaffold of sturdy structure, sufficiently rigid to meet all working requirements in limited space, yet sufficiently open in framework to permit working ease within and around the scaffold with a minimum of climbing over parts of the structure.

Still another object is to provide a scaffold of tubular members with a reinforced corner joint of sufficient stability to eliminate cross member reinforcing.

Various other objects and advantages of this invention will more fully appear during the course of the following specification and will be particularly pointed out in the appended claims.

One form of the invention in the assembled form, with details of the several elements, is shown in the accompanying drawings, in which:

Figure 1 is a perspective view of the assembled scaffold in elevation;

Figure 2 is an exploded view of a vertical corner joint;

Figure 3 is an exploded view of the base assembly at a corner;

Figure 4 is an exploded view of the corner post, top rail assembly.

Figure 5 is an exploded view of an alternate form of corner post assembly.

Figure 6 is a sectional detail in elevation of the corner post assembly of Figure 5 in closed position.

Referring to Figure 1 it will be seen that the scaffold is composed of a limited number of different shapes. Individually the shapes are limited in size and configuration to approach tubular structural limits. This requires minimum openings for the passage of the separate elements and permits ease of assembly in limited space. The sequence of assembly is easily understood, aiding construction in confined quarters, and, once assembled as shown, presents a rigid support for workmen.

In this figure, the corner posts 10 are one of the members duplicated throughout the structure. These elements, of equal length and diameter measurements, space the corner connecting members at equal elevations.

The corner connectors include tubular members 12, and 21 with hubs on each end. These connectors, form-

2

ing ledgers in that they are laid horizontally, are made with two different sized hubs. The tubular members 12 and 21 connect either hubs 14 of smaller size, or hubs 16 of larger size, respectively.

Figure 2 illustrates the use of these different ledger members in assembling a corner. The member with the smaller hubs 14 is equal in diameters, external and internal, to the corner posts 10. A pin member 18 is fitted into the hub 14 having an external diameter equal to the internal hub and corner post diameter. Pin 18 may be either permanently attached to hub 14, making a complete corner reinforcing member, or may be placed as each corner is assembled where the limitations of space require. This figure also includes the larger hub 16 which has an internal diameter equal to the external diameter of the corner post 10. Such relative diameter sizes permit the corner post 10 to embrace the pin 18 and in turn be enclosed in the hub 16. It is evident that a rigid corner construction is the result.

As a matter of protection for those who use the structure, a top railing assembly is added. Without this safety section, the structure consists simply of three different elements, four if pin 18 is counted separately. This addition requires modified or capping corner posts 11, same diameter as posts 10, with the upper end closed to hold the stud 13. Tubular members 19, flattened on the ends and drilled to fit over the stud 13, are the top rails being held by wing-nuts 17.

The capping corner posts 11, as indicated above, are partially interchangeable with corner posts 10; partially interchangeable because they are limited to closing the top of the scaffold, yet can be used over the pin 18 and in the hubs 16 as indicated in Figure 5. In this figure showing a variation of the structure already described, the capping corner post 11 has been substituted for corner post 10 showing a top corner joint instead of an intermediate corner joint as shown in Figure 2.

In Figures 5 and 6, to increase the rigidity and stability of the structure beyond that indicated in Figures 1, 2 and 4 presently described, hub 14 is increased in thickness until its external diameter equals the external diameter of hub 16, yet retains the internal diameter of pin 18. This thicker hub is denoted by the numeral 15 connected by tubular member 23 as shown in Figures 5 and 6. The sectional view of this corner joint in the closed position illustrated in Figure 6 shows the completed connection. The assembly is made as already described in discussing Figure 2. By reason of the increased thickness of hub 15 (over original thickness of hub 14, Figure 2) the bearing surfaces between the elements is increased as they are connected in fixed alignment.

The one remaining figure of the drawing yet to be described, Figure 3, will be better understood if it is described in the discussion of the operation of the device. If Figure 1 is considered together with Figure 3, it will be apparent that this scaffold rests on a base built of these elements. A square is formed of four ledger members with the larger hubs 16. As corner posts 10 insert in these hubs, the double hub depth on all four corners supports the initially erected corner posts in the vertical position.

Ledger members of the smaller dimensioned hubs 14 are then placed to engage opposite pairs of corner posts 10. These ledgers are held in place and abutting the ends of corner posts 10 by means of pin 18. On the upwardly projecting portion of the pin 18, and arranged to connect the corners not connected by the members with hubs 14, the hub 16 ledgers are placed. Corner posts 10 are then inserted in hubs 16 and over the pin 18, being pressed down to rest on the shoulder of hub 14. The elevation of the structure parallel with the bottom

ledger is maintained as each corner post is separated only by the uniform length of hub 14.

This structure procedure is continued, using either the hub 14 member or the variation hub 15 until the top is reached when capping corner posts 11 are substituted for corner post 10 and the top rails 19 are fastened into place. The choice of hub 14 or 15 is not one of construction difference as both are erected the same. Each type has its advantage of lighter weight or increased rigidity and both will serve equally.

By reversing the operation, the scaffold can be as easily disassembled. The simplicity of the elements reduces maintenance and requires no tools for handling. Assembly and disassembly can be accomplished in a minimum of space with a minimum of work. The number of elements of different shapes is reduced to a minimum, and an open scaffold permitting comparatively free movement in restricted space yet of sturdy, usable construction is provided.

What is claimed is:

1. A scaffold of successive tiers comprising a base tier of interchangeable corner posts, first type ledger members with hub ends of an internal diameter equal to the external diameter of the corner posts positioned to receive and hold said corner posts in the hubs; and additional tiers including a pair of second type ledger members with hub ends of an internal diameter equal to the internal diameter of the corner posts placed on top of opposed pairs of corner posts, pin members extending through the hub ends extending above and below the same holding the corner posts below and positioned to receive corner posts above said hubs, and a pair of ledger members with hub ends of internal diameter equal to the external diameter of the corner posts connecting corners unconnected by said first pair of ledger members and transverse thereto, and corner posts inserted in said pair of first type ledger member hubs to embrace the pin members positioned by the pair of second type ledger members reinforcing the corners of successive tiers of the scaffold.

2. The scaffold as defined in claim 2 further characterized by the highest tier being modified to include capping corner posts adapted to fit into the hubs of the pair of first type ledger members to embrace the upwardly projecting pin from the hubs of the pair of second

type ledger members, each of said capping corner posts being closed at the top by a stud projection, top rails apertured to fit over said stud projections, and fastening means to engage the studs and hold the top rails in position.

3. A scaffold comprising a plurality of sets of four transversely extending tubes extending in different horizontal planes, the lower set comprising four tubes each having end hubs, a plurality of sets of vertically extending tubular posts, the lower ends of the lower set of posts extending into the end hubs of the lower set of tubes; two opposed tubes of an upper set having end hubs of smaller diameter than those of the lower set and having pins adapted to extend into the upper ends of the posts of the lower set and into the lower ends of the upper set of posts, the other two members of the upper set comprising tubes with end hubs into which extend the lower ends of an upper set of posts; and four transversely extending reinforcing members secured to the upper ends of the uppermost set of posts.

4. Coupling means having, in combination, vertical tubular corner posts of a demountable scaffold, a first type ledger member with hub end, said hub having internal and external diameters equal to like diameters of the tubular corner posts, a pin member of an external diameter equal to the tubular corner post internal diameter extending through the hub end of the first type ledger member and engaging with said corner posts, and a second type ledger member having hub end of an internal diameter equal to both the external diameter of the tubular corner posts and the hub of the first type ledger member, the hub of the second type ledger member resting on said first type ledger member and engaging the hub thereof and the pin engaged corner post in said hub.
